Primary Examiner — Wendy L Arminio*Assistant Examiner* — Carrie S Gelula(74) Attorney, Agent, or Firm — Hanley, Flight & Zimmerman, LLC(57) CLAIM

The ornamental design for a monitor shelf, substantially as shown and described.

DESCRIPTION

FIG. 1 is a perspective view of a monitor shelf, showing our new design;

FIG. 2 is a bottom view thereof;

FIG. 3 is a top view thereof;

FIG. 4 is a rear view thereof;

FIG. 5 is a front view thereof;

FIG. 6 is a first side view thereof; and,

FIG. 7 is a second side view thereof.

The broken lines in the drawings are for the purpose of illustrating portions of the monitor shelf that form no part of the claimed design.

1 Claim, 7 Drawing Sheets(56)
